UNITED STATES PATENT OFFICE.

ALBERT E. KILNER, OF BALTIMORE, MARYLAND.

DESIGN FOR A DISPLAY-HOLDER.

SPECIFICATION forming part of Design No. 26,498, dated January 5, 1897.

Application filed December 1, 1896. Serial No. 614,137. Term of patent 7 years.

To all whom it may concern:

Be it known that I, ALBERT E. KILNER, a citizen of the United States, residing at Baltimore, in the State of Maryland, have invented a new and original Design for Display-Holders, of which the following is a specification.

This invention relates to a new and original design for display-holders; and it has for its object to provide a design of this character that shall be both useful and ornamental.

The leading feature of the design resides in a flat oblong rectangular body provided at its opposite longitudinal edges with forwardly-disposed flange portions of an L-shape in cross-section and having its opposite end edges scalloped to form outwardly-projecting semicircular lobes and narrow oblong flat projections having rounded outer ends and disposed in the reentrant spaces formed at the opposite sides of said lobes.

In the drawings, Figure 1 is a perspective view of a display-holder embodying the here-

in-described design. Fig. 2 is a transverse sectional view thereof.

Referring to the accompanying drawings, the numeral 1 designates a flat oblong rectangular body provided at its opposite longitudinal edges with forwardly-disposed flange portions 2 of an L shape in cross-section. The opposite end edges of the body 1 are scalloped to form outwardly-projecting semicircular lobes 3, reentrant V-shaped spaces 4 at opposite sides of said lobes, and narrow oblong flat projections 5, disposed in said reentrant spaces and having rounded outer ends 6.

What I claim is—

The design for a display-holder herein shown and described.

In testimony that I claim the foregoing as my own I have hereto affixed my signature in the presence of two witnesses.

ALBERT E. KILNER.
